UNITED STATES PATENT OFFICE.

ELI J. MILLER, OF YORK, PENNSYLVANIA.

DISH-WASHER.

No. 829,434.

Specification of Letters Pat. No. 829,434.
Application filed August 9, 1905. Serial No. 272,699.

Patented Aug. 26, 1908.

To all whom it may concern:

Be it known that I, ELI J. MILLER, of York, in the county of York and State of Pennsylvania, have invented a new and useful Improvement in Dish-Washers, of which the following is a specification, reference being had to the accompanying drawings, illustrating the invention.

My invention consists of a rotary dish-washer, preferably cylindrical in form, formed in two parts and provided on its interior with a perforated lining bent or arched to form pockets, cells, and carriers and supported by end posts or plates braced at their lower ends and a stationary dish-receptacle within the casing.

The purpose of this invention is to provide simple and efficient means for washing dishes in a rapid manner, inexpensive, and convenient.

The cylindrical drum or casing is partly filled with hot water to wash the dishes. The casing or drum is now revolved by any suitable means. Thus a large part of the body of the water is carried upward to a certain angle and discharged onto the dishes and receptacles, finding its way to the bottom to be again used. The dirty water is now drawn off by releasing the stopper shown or by lifting or releasing the upper part of the casing. The lower part can be tilted or the water thrown out bodily into a vessel or sink. A clean supply of hot water is now provided; the casing again revolved and when done the water is again drawn off or thrown out and the dishes, being hot, dry themselves.

My invention is disclosed in the following description and accompanying drawings, in which—

Figure 1 is a plan view with the upper part of the cylinder thrown back. Fig. 2 is a vertical longitudinal section, and Fig. 3 a transverse section on the line xx of Fig. 2. Fig. 4 is a detailed view showing the mounting of shaft 9.

My device comprises a revolving drum, preferably of a cylindrical shape and divided into two parts on or near the medial line, as clearly shown in Fig. 3. Inside the cylindrical drum 1 a semicylindrical dish-receptacle 22 is non-rotatably supported. The drum is mounted for rotation upon a suitable frame or stand 2, which consists of two upright posts 3, connected by suitable framing and bracing. These posts are provided with slots or grooves 4 and 5, respectively. In

the slot 4 of the left-hand post 3 is non-rotatably held the end of a bolt 6. To an enlargement 6' at the opposite end of the bolt 6 is secured a cross-bar 8, over which hooks 21, 60 on the end of the dish-receptacle 22 engage. The bolt 6 passes through a suitably reinforced aperture in the lower half of the drum 1, which turns freely upon the bolt 6 as a pivot. A shaft 9 is located at the opposite end of the machine. The shaft is provided with a crank 10 and handle 11. It has a shoulder or collar 29 to keep it in place against the post 3, and its inner end is prolonged to support the dish-holder 22, a slotted bearing-plate 21 being secured to the end of the shaft 9. This shaft 9 is in line with bolt 6, and the two together rotatably support the cylinder or water-holder and non-rotatably support the dish-holder.

The cylinder, as stated, is made in two parts. The lower part is provided with a projection 12 around its upper edge, forming a groove or packing-seat, preferably V-shaped, provided with a sheeting or packing 25, into which the lower edge of the upper section, which has been bent back upon itself to form a substantially V-shaped head 13, may fit and conform and form a substantially water-tight joint. The lower part has around or near its upper edge and below the groove a bead or piping 14. Seated against and below this bead 14 at either side is a partly-perforated strip of sheet metal 15, extending around the interior of this portion of the cylinder or water-holder of the shape shown—that is, consisting of several curved or arched portions extending around the inner circumference of the casing. This is sprung in behind the beading and forms with the curved side of the cylinder a series of pockets, cells, or carriers. It can at any time be removed to be cleaned and sprung back into place when desired. The upper half of the cylinder is provided with a series of similar pockets formed in the same way, the sheet metal in this case being sprung behind the inturned V-shaped edge portion of the casing. I provide handholds 35 upon the lower part of the cylindrical drum for convenience in removing the same from its supports.

The two parts of the cylinder may be secured together by any suitable means. I have shown them as secured together by the hooked straps 16, which are passed under the eyes 17 and at the opposite end are held

down by the pivoted levers 19 and hooks 20, whereby the two parts of the cylinder are held firmly together. The eyes 17 are each provided with a screw 26 and nuts 27, where-
5 by the position of such eyes above the brackets 28 may be changed or regulated to suit any wear or warping of either part of the wa-
ter-receptacle or of any other part.

The dish-receptacle 22, as will be seen, is
10 removably supported by means of the hooks
21, taking over the bar 8 at one end, and the
slotted bearing-plate 21', resting upon the
shaft 9 at the other end. Handles 30 are
15 provided upon the receptacle 22, so that the
latter may be readily lifted out of the ma-
chine. The dish-receptacle is of open-work
construction, its ends being perforated, as
20 shown in Fig. 3, and its sides and bottom
being, as shown, made up of perforated strips.

25 At 24 I have shown what may be termed
"feet." These are pivoted to the bottom of
the lower part of the cylinder and may be
turned, as shown in Fig. 3, when it is desired
25 to lift the cylinder out of its frame by the
handholds 35 and stand it on a table or floor,
so as to support the lower part of the cylinder
securely or the entire cylinder of the casing.
After the dish-tray has been placed in position
30 and the lower part of the cylinder has been
partly filled with hot water and lye or soap, if
needed, the upper part is fastened down and
the cylinder turned by the crank shown or by
any other means. The water caught and car-
ried up by the pockets or carriers is discharged
35 through the perforations of the plate 15 onto
and between the dishes, keeping up a con-
stant circulation. At the conclusion of the
operation the water may be drawn off at 23,
the cylinder being thereafter filled with the
40 rinsing-water, or the whole body of the water
in the casing may be discharged into a vessel
or sink after the upper part has been turned
back by turning the handle or casing.

I claim—

45 1. The combination, with a rotatable wa-
ter-holding drum having its axis substan-
tially horizontal, and provided on its inner
periphery with inclosed water-elevation pock-
ets closed exteriorly by the wall of the drum
50 and having perforations in their inner walls
substantially as described, of a dish-holder
mounted within the drum and arranged to
receive the water discharged from the per-
forations of the pockets.

55 2. In a dish-washing machine, the combi-
nation of a rotating imperforate water-holder
provided on its interior with a perforated lin-
ing bent or arched so as to form pockets or
cells, and a stationary dish-holder.

60 3. In a dish-washing machine, the combi-
nation of a rotating imperforate water-holder
provided on its interior with a perforated de-
tachable lining bent or arched so as to form
pockets or cells, and a stationary dish-holder.

65 4. A dish-washer comprising a cylindrical

casing provided with means for mounting it
upon posts for rotation, and rotatable legs
70 attached to its bottom for supporting it in an
upright position when removed from the
posts, said legs being adjustable to be kept
out of the way during the rotation of said
washer.

5. A dish-washer comprising an upper and
a lower casing and a stationary dish-holder,
75 said lower casing being provided on its bot-
tom with horizontally-rotatable legs or sup-
ports which can be turned substantially par-
allel with and coincident with the bottom or
turned at an angle thereto to support said
80 lower casing, forming feet.

6. In a dish-washing machine, the combi-
nation, with a water-holder, of a trunnion
passing through one end of the water-holder
and arranged to support the same, means for
supporting the opposite end of said water-
holder, a cross-piece inside the water-holder
85 and united to the trunnion, and a dish-hold-
ing tray within the water-holder and pro-
vided with means for detachably engaging
said cross-piece at one end and means for
90 supporting the opposite end of said dish-
holder.

7. In a dish-washing machine, the combi-
nation with a water-holding drum formed in
95 two parts, each part being substantially one-
half of the drum, of a plurality of screw-eyes
adjustably secured to one of the parts of the
drum and adjustable with relation thereto,
straps provided with hooks engaging the re-
spective screw-eyes, said straps bearing on
100 the other part of the drum, levers engaging
the ends of the straps, and means for holding
said levers in their locking position.

8. In combination, a rotatable, two-part
drum, means to secure the parts thereof to-
105 gether, stops adjacent the meeting edges of
each of the parts thereof, perforated metal
linings in each of the parts and retained in
place behind the stops and spaced away from
the walls of the drum at intervals, and a sta-
110 tionary dish-receptacle in said drum.

9. In combination, a rotatable two-part
drum, means to secure the parts thereof to-
115 gether, stops adjacent the meeting edges of
the parts, a perforated lining resting against
the walls of the drum at intervals and spaced
away therefrom between the regions where it
rests thereon and held in place by the stops,
and a stationary dish-receptacle in the said
120 drum.

10. The combination of a horizontal, cy-
lindrical drum divided into two parts slightly
above the middle thereof, means to rotatably
support the lower part of the drum, stops ad-
125 jacent the meeting edges of the two parts of
the drum, perforated linings spaced away at
intervals from the walls of the drum and re-
tained in place by being sprung in behind the
stops, and a stationary dish-receptacle in
130 said drum.

11. The combination with a drum, of a crank-shaft secured centrally thereto at one end thereof and extending within the drum, a dish-receptacle in the drum and having at 5 one end a bearing for the said inwardly-projecting end of the crank-shaft, a bolt, a cross-head thereon, hooks on the end of the dish-receptacle opposite the crank-shaft to engage over the cross-head, there being an opening 10 in the drum through which the bolt passes, stops on the inside of the drum, a perforated lining in the drum and held in place behind the stops, and a frame wherein the bolt is supported non-rotatably and wherein the 15 shaft is supported rotatably.
12. In a dish-washer, the combination with a rotatable imperforate water-holding drum having its axis substantially horizontal, of a stationary dish-holder mounted within 20 the drum, and an arched perforated lining
- attached to the inner periphery of the drum and arranged to form pockets, substantially as described, said pockets being closed exteriorly by the drum.
13. In a dish-washer, the combination ²⁵ with a rotatable imperforate water-holding drum having its axis substantially horizontal, of a stationary dish-holder mounted within the drum, and an arched perforated lining removably attached to the inner periphery ³⁰ of the drum and arranged to form pockets, substantially as described, said pockets being closed exteriorly by the drum.

In testimony whereof I hereunto sign my name, this 3d day of August, 1905, in the presence of two subscribing witnesses.

ELI J. MILLER.
